DESIGN FOR A GLOVE

William S. Hatch, Gloversville, N. Y.

Application February 11, 1937, Serial No. 67,585

Term of patent 14 years

To all whom it may concern:

Be it known that I, William S. Hatch, a citizen of the United States of America, residing in Gloversville, county of Fulton, and State of New York, have invented a new, original, and ornamental Design for a Glove, of which the following is a specification, reference being had to the accompanying drawing, forming part thereof, wherein,

My design is characterized by the combination of the three specific types of stitches applied to the specific portions of a man's glove as shown.

I claim:

The ornamental design for a glove, substantially as shown, and described.

WILLIAM S. HATCH.
